UNITED STATES PATENT OFFICE.

THEODORE R. TREIBER, OF CHICAGO, ILLINOIS.

DOUBLE-HUNG WINDOW CONSTRUCTION.

Application filed October 17, 1927. Serial No. 226,593.

The main object of my invention resides in the provision of a simple and effective double hung window construction all with a view toward providing such a construction which is well adapted for its purpose, convenient in use, economical of manufacture, and adaptable to window constructions of the present double sliding sash type.

With this object in view my invention consists in certain features of novelty in the construction, combination, and arrangement of parts by which the said object and certain other objects, hereinafter appearing, are effected, all as fully described with reference to the accompanying drawings and more particularly pointed out in the appended claims.

In the said drawings—

Figure 1 is an interior face view of a double hung window construction embodying my invention, with parts broken away and in section;

Figure 2 is a side elevation of the same with parts omitted and in section;

Figure 3 is a view similar to Figure 2 showing the sash in positions of their movement different from those in which they are shown in Figure 2;

Figure 4 is a partial sectional view on the line 4—4 of Figure 2;

Figure 5 is a partial sectional view on the line 5—5 of Figure 2;

Figure 6 is a partial sectional view on the line 6—6 of Figure 2;

Figures 7 to 11 inclusive are perspective views of different parts of the mechanism, hereinafter described;

Figure 12 is a rear elevation of a partial assembly of one portion of the mechanism hereinafter described; and

Figure 13 is a perspective view of another part of the mechanism, hereinafter described.

Like characters of reference indicate like parts in the several views.

Referring to the drawings, 1 designates an upright window frame and 2 designates sash, of which there are two as usual, which cooperate to close the window opening of the frame. See Figures 1 and 2. As shown both the frame and sash are of the usual wood construction, though it will be obvious that the

invention is not confined to a wood construction, and the frame is provided at opposite sides thereof with usual window weight enclosures 3. See Figures 1, 4, 5, and 6.

Each of the sash 2 is carried for movement with respect to the frame 1 in a similar manner, and for the purpose of brevity a detailed description of the means whereby but one of the sash is carried will be given, it being understood that the description is applicable to the carrying means of both sash and the reference characters relating thereto being applied to both of such carrying means on the drawings.

The frame 1 is provided with vertical opposing grooves 4 at opposite sides thereof, and the sash 2 has attached thereto, on opposite sides at the lower corners thereof, transversely or horizontally aligned clutch lugs 5 which are disposed correspondingly with the plane of the sash and are slidably engaged in the grooves 4 for vertical movement of the sash in its plane with respect to the frame 1. See Figures 2, 5, 6, and 7. The sash 2 is provided at opposite sides thereof with longitudinal grooves 6, and lugs 7 are attached to the frame 1 on opposite sides thereof and are slidably engaged in the grooves 6 for cooperation with the grooves 4 and lugs 5 to guide the sash for vertical movement in its plane. See Figures 2, 4, 6, and 13.

Mortised into the inner faces of the opposite sides of the frame 1 adjacent the lower ends of the grooves 4 are transversely or horizontally spaced bearing plates 8 which are provided with transversely or horizontally aligned bores 9 therethrough. See Figures 1, 2, 6, 11, and 12. Pivoted mounted in the bores 9 of the bearing plates 8 are clutch members 11 which are provided with clutch grooves 12 forming a part of the grooves 4 for engagement with the clutch lugs 5 to provide a pivot for angular facewise movement of the sash, the grooves 6 being provided with lateral openings 13 for the passage therethrough of the lugs 7, engaged in the grooves 6 when the sash is positioned in its vertical movement for angular movement thereof, in the angular movement of the sash, thus permitting this angular movement.

The clutch lugs 5 consist of attaching portions 14 of right angle formation which are mortised into the lower corners of the sash 2 and secured thereto and the clutch lug portions proper 5 which are connected at their lower ends to the attaching portions, as designated at 15, and which are disposed in spaced relation with the attaching portions 14. See Figure 7. Horizontally disposed 10 screws 16 pass through bores in the clutch lugs 5 and the attaching portions 14 and are screwthreaded into the sash, and window weight cord hooks 17, see Figure 8, are pivotally engaged with the screws 16 between the 15 attaching portions 14 and the clutch lugs 5 and are slidably engaged in the grooves 4. The free ends of the hooks 17 are offset away from the sash, as designated at 18, and are apertured, as designated at 19, for the attachment thereto of window weight cords 21 which extend upwardly therefrom in the 20 grooves 4 to weight cord pulleys 22 of usual construction over which they are trained for connection with weights 23 in the weight 25 closures 3 of the frame to counterbalance the sash in its vertical or bodily movement. See Figures 1, 2, 3, and 6.

The screws 16 are disposed approximately at the axis of angular movement of the sash 30 so that the weight cords 21 are pivotally connected with the sash approximately at said axis with the result that the position of the weight cords is substantially unchanged in the angular movement of the sash and they 35 remain in their advantageous positions in the grooves 4.

The clutch members 11 are provided with axial spindles 24 which project in the window weight enclosures 3. See Figures 1, 6, and 40 9. Pins 25 are secured in diametrically disposed bores in the spindles 24 at the outer ends thereof, and torsional springs 26 surround the spindles 24 within the enclosures 3 and have ends thereof secured with the pins 45 25 and have the other ends thereof engaged between lugs 27 on the inner faces of the bearing plates 8. See Figures 1, 6, 11, and 12, of which Figure 12 shows a spring 26 in broken lines so as not to obscure other structure 50 shown in this figure.

In the preferred arrangement the sash 2 swings inwardly, and the springs 26 yieldably urge the sash in its angular movement into its vertical position, thus resisting angular 55 movement of the sash out of its vertical position and counterbalancing the same in its said angular movement. The springs 26 are axially compressed in their assembly with the bearing plates 8 and the clutch members 11 60 so that they maintain frusto-conical bearing surfaces 28 on the inside of the main portions or heads of the clutch members 11 engaged with corresponding surfaces 29 in the bores 9 of the plate 8, thereby maintaining the 65 clutch members 11 in proper bearing engage-

ment with the bores 9 of the plates 8. See Figures 6, 9, and 11.

Stop means are provided which are operative upon the clutch members 11 and oppose the springs 26 to normally position the clutch 70 members in angular positions corresponding with the vertical position of the sash, that is, to normally position the clutch members 11 with the grooves 12 thereof aligned with the grooves 4, and consist of the following. See 75 Figures 9, 11, and 12. Formed on the clutch members 11 immediately inward of the main portions or heads of the clutch members 11 are segmental stop formations 31 which operate in the bores 9 of the plates 8 immediately inward of the bearing surfaces 29 of these bores. Formed in the bores 9 of the plates 8 in angular alinement with the stop formations 31 are stop formations 32 which abut the stop formations 31 in the angular 80 movement of the clutch members 11 with respect to the bearing plates 8 to limit movement of the clutch members 11 as aforesaid and in addition to limit movement of the sash out of its vertical position and in a position 85 where the sash lies in a substantially horizontal plane.

As aforesaid the grooves 6 are provided with lateral openings 13 for the passage therethrough of the lugs 7 engaged in the 90 grooves 6 of the sash when the sash is positioned in its vertical movement for angular movement thereof. Referring to the lower sash, this sash is provided with two pairs of 95 transversely spaced openings 13 for the release of correspondingly disposed pairs of transversely alined lugs 7. See Figures 2 and 3. The lower pair of the lateral openings on the lower sash are outlined by plates 33 mortised into the sides of the sash and secured thereto and provided with groove 100 formations 34 forming part of the grooves 6. See Figures 2, 3, and 10. The portions of the plates 33 margining the upper ends of the corresponding openings 13 are provided with notches 35 facing downwardly in these openings and which are engageable with the lowermost pair of lugs 7 in the angular movement of the lower sash to position this sash 105 in an intermediate or ventilating position of its angular movement, as shown in broken lines in Figure 3, it being noted that when so positioned this sash is positively positioned so that draughts of air cannot change the 110 position of the sash. Engagement of the notches 35 with the associated lugs 7 is effected by first swinging the sash on its pivotal axis to its ventilating position and then engaging the notches 35 with the associated lugs 7 by downward movement of the sash, the sliding engagement of the clutch lugs 5 with the grooves 12 of the clutch members 115 permitting this movement. Further inward angular movement of the lower sash or movement of the same into its vertical position 120 125 130

from its ventilating position is effected by bodily lifting this sash to disengage the notches 35 from the associated lugs 7 and moving the sash angularly in the proper direction.

The heads or main portions of the clutch members 11 are countersunk into the portions of the frame 1 forming the grooves 4 and these portions of the frame are cut away about the clutch members 11, as designated at 36 in Figures 2, 3, and 6, to limit bodily movement of the sash in their planes while they are out of their vertical positions by engagement with the ends of the clutch lugs 5, this engagement permitting sufficient bodily movement of the lower sash in its plane to engage and disengage the notches 35 with the associated lugs 7.

The openings 13 of the upper sash 2 extend completely across the sides of this sash so that this sash may pass certain lugs 7 associated with the lower sash 2 as clearly shown in Figure 2.

When both of the sashes 2 are in their closed positions they may be locked in a usual manner by means of a usual window latch 37, as shown in Figures 1 and 2.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a double hung window construction the combination with frame and sash elements of pivotally mounted clutch means on one of said elements, a second clutch means fast on the other of said elements and engaging with said pivoted clutch means to angularly fix said other element with said pivoted clutch means for angular facewise movement of the sash element and movable with respect thereto with bodily movement of the sash element in its plane and normal to the axis of its said angular movement, and means operative upon said pivoted clutch means for resisting angular movement of the sash element out of the plane of its bodily movement.

2. In a double hung window construction the combination with frame and sash elements, of clutch means pivotally mounted on one of said elements on a horizontal axis transverse to the window, a second clutch means fast on the other of said elements and engaging with said pivoted clutch means to angularly fix said other element with said pivoted clutch means for angular facewise movement of the sash and movable with respect thereto with vertical movement of the sash element in its plane, and means operative upon said pivoted clutch means for coun-

terbalancing the sash element in its said angular movement.

3. In a double hung window construction the combination with frame and sash elements, of clutch means pivotally mounted on one of said elements on a horizontal axis transverse to the window, a second clutch means fast on the other of said elements and engageable with said pivoted clutch means to angularly fix said other element with said pivoted clutch means for angular facewise movement of the sash element and disengageable therefrom with vertical movement of the sash element in its plane, spring means operative upon said pivoted clutch means for yieldably urging the sash element in its angular movement into its vertical position, and stop means operative upon said pivoted clutch means and opposing said spring means to normally position said pivoted clutch means in an angular position corresponding with the vertical position of the sash element.

4. In a double hung window construction the combination with a sash and a frame provided with window weight enclosures at opposite sides thereof, of a pair of grooved clutch members pivotally mounted on opposite sides of the frame on a horizontal axis and provided with axial spindles projecting in said weight enclosures, a pair of clutch lugs fast on opposite sides of the sash in transverse alignment and arranged corresponding with the plane of the sash and engageable with the grooves of said pivoted clutch members to angularly fix the sash therewith for angular facewise movement of the sash and disengageable therefrom for vertical movement of the sash in its plane, torsional springs surrounding said spindles within said weight enclosures and operative upon said pivoted clutch members to yieldably urge the sash in its angular movement into its vertical position, and stop means operative upon said pivoted clutch members and opposing said springs to normally position said pivoted clutch members in angular positions corresponding with the vertical position of the sash.

5. In a double hung window construction the combination with frame and sash elements, of groove means on one of said elements, clutch lug means fast on the other of said elements and slidably engaging in said groove means for bodily movement of the sash in its plane, grooved clutch means forming a part of said groove means and pivotally mounted on the other of said elements for engagement with said clutch lug means for angular facewise movement of the sash element on an axis transverse to its said bodily movement, and means operative upon said grooved clutch means for resisting angular movement of the sash element out of the plane of its said bodily movement.

6. In a double hung window construction

the combination with a frame and a sash, of vertical groove means on the frame, clutch lug means fast on the sash and arranged correspondingly with the plane thereof and slidably engaged in said groove means for vertical movement of the sash in its plane, grooved clutch means forming a part of said groove means and pivotally mounted on the frame and engageable with said clutch lug 10 means to provide angular facewise movement of the sash on a horizontal axis, and spring means operative upon said grooved clutch means to yieldably urge the sash into its vertical position.

15 7. In a double hung window construction the combination with a frame and a sash, of means carrying the sash for movement with respect to the frame including opposing grooves on opposite sides of the frame and 20 transversely alined clutch lugs fast on opposite sides of the sash and disposed correspondingly with the plane of the sash and slidably engaged in said grooves for movement of the sash in its plane, grooved clutch members 25 forming a part of said grooves and pivotally mounted on opposite sides of the frame and engageable by said lugs to provide a pivot for angular facewise movement of the sash on an axis transverse to its first mentioned movement, spring means operative upon said grooved clutch members to yieldably urge the sash into the plane of its first mentioned movement, and stop means opposing said spring means for normally positioning said pivoted members with their grooves in alinement with said first mentioned grooves.

8. In a double hung window construction the combination with a frame and a sash, of 40 slide bearing means comprising groove means and plural lug means spaced therealong, one of said lug means being clutch lug means, pivotally mounted grooved clutch means forming a part of said groove means and slidably engaging said clutch lug means to provide a pivot including said clutch lug means for angular facewise movement of the sash on an axis transverse to the first mentioned movement thereof, the remainder of said 45 clutch lug means being releasable from said groove means for said angular movement of the sash, and means operative upon said grooved clutch means to resist angular movement of the sash out of the plane of its first mentioned movement.

55 9. In a double hung window construction the combination with a frame and a sash, opposing grooves on opposite sides of the frame, a pair of transversely alined clutch 60 lugs on opposite sides of the sash and arranged correspondingly with the plane thereof and slidably engaged in said grooves, longitudinal grooves on opposite sides of the sash, lugs on opposite sides of the frame and 65 slidably engaged in said second mentioned

grooves for cooperation with said first mentioned grooves and lugs to guide the sash for movement in its plane, grooved clutch members pivotally mounted on opposite sides of said frame and forming a part of said first mentioned grooves for engagement with said clutch lugs for angular facewise movement of the sash on an axis transverse to said first mentioned movement thereof, said second mentioned grooves being provided with lateral openings for the passage therethrough of said second mentioned lugs in the angular movement of the sash, springs operative upon said pivoted members to resist angular movement of the sash out of the plane of its first mentioned movement, and stop means operative upon said pivoted members and opposing said springs to normally aline the grooves of said pivoted members with the remainder of said first mentioned grooves.

10. In a double hung window construction the combination with a frame and a sash, of means carrying the sash for vertical movement in its plane and angular facewise movement on a horizontal axis, and window 90 weight cords pivotally connected with the sash approximately at the axis of angular movement thereof.

11. In a double hung window construction the combination with a frame and a sash, of means carrying the sash for vertical movement in its plane and angular facewise movement on a horizontal axis including opposing grooves on opposite sides of the frame and transversely alined lugs on the sash and slidably engaged in said grooves and forming a part of the pivot means for said angular movement of the sash, and window weight cords extending in said grooves and pivotally connected with the sash approximately 100 at the axis of angular movement thereof.

12. In a double hung window construction the combination with a frame and a sash, opposing vertical grooves on opposite sides of the frame, transversely alined lugs on the sash and slidably engaged in said grooves and forming a part of a pivot means for angular facewise movement of the sash on a horizontal axis, additional guide means cooperating with said grooves and lugs for guiding the sash for vertical movement in its plane and releasable to permit said angular movement of the sash, and window weight cords extending in said grooves and pivotally connected with the sash approximately at the axis of angular movement thereof.

13. In a double hung window construction the combination with a frame and a sash, of opposing vertical grooves on opposite sides of the frame, transversely alined clutch lugs fast on the lower portion of the sash and arranged correspondingly with the plane of the sash and slidably engaged in said grooves, grooved clutch members forming lower portions of said grooves and pivotally mounted on oppo- 125 130

- site sides of the frame on a horizontal axis and engageable with said lugs to angularly fix the sash therewith for angular facewise movement of the sash, means operative upon 5 said pivoted clutch members for counterbalancing the sash in its said angular movement, additional guide means cooperating with said grooves and lugs for guiding the sash for vertical movement in its plane and releasable to 10 permit said angular movement of the sash, and window weight cords extending in said grooves and pivotally connected with the sash approximately at the axis of angular movement thereof.
14. In a double hung window construction the combination with a frame and a sash, of opposing vertical grooves on opposite sides of the frame, transversely alined clutch lugs fast on the lower portion of the sash and arranged correspondingly with the plane of the sash and slidably engaged in said grooves, grooved clutch members forming lower portions of said grooves and pivotally mounted on opposite sides of the frame on a horizontal 25 axis and engageable with said lugs to angularly fix the sash therewith for angular facewise movement of the sash, means operative upon said pivoted clutch members for counterbalancing the sash in its said angular movement, additional longitudinal grooves on opposite sides of the sash, additional lugs on opposite sides of the frame and slidably engaged in said last mentioned grooves for cooperation with said first mentioned lugs 30 and grooves to guide the sash for vertical movement in its plane, said last mentioned grooves being provided with lateral openings for release of said last mentioned lugs for angular movement of the sash, and window weight cords extending in said first mentioned grooves and pivotally connected with the sash approximately at the axis of angular movement thereof.
15. In a double hung window construction the combination with a frame and a sash, of vertical groove means on said frame, clutch lug means fast on the sash and arranged correspondingly with the plane thereof and slidably engaged in said groove means for vertical movement of the sash in its plane, grooved clutch means forming a part of said groove means and pivotally mounted on the frame for engagement with said clutch lug means to provide angular facewise movement 55 of the sash on a horizontal axis, window weight cords extending in said grooves and pivotally connected with the sash approximately at the axis of angular movement thereof, spring means operative upon said grooved clutch means to yieldingly urge the sash into its vertical position, and lug means and notched member means for positioning the sash in its said angular movement and engageable and disengaging with movement of 60 the sash in its plane and corresponding with the direction of said vertical movement thereof.
16. In a double hung window construction the combination with a frame and a sash, of slide bearing means providing vertical movement of the sash with respect to the frame and comprising groove means and plural lug means spaced therealong, one of said lug means being clutch lug means, pivotally mounted grooved clutch means forming a 70 part of said groove means and slidably engaging said clutch lug means to provide a pivot including said clutch lug means for angularly facewise movement of the sash on a horizontal axis, said groove means being provided with lateral opening through which the remainder of said lug means pass in the angular movement of the sash, spring means operative upon said grooved clutch means to yieldably urge the sash into its vertical position, window weight cords pivotally connected with the sash approximately at the axis of angular movement thereof, and notched means releasably engageable with said remainder of said lug means to position the sash 80 in its said angular movement.
17. In a double hung window construction the combination with a frame and a sash, of opposing vertical grooves on opposite sides of the frame, a pair of horizontally alined clutch lugs fast on opposite sides of the lower portion of the sash and arranged correspondingly with the plane thereof and slidably engaged in said grooves, longitudinal grooves on opposite sides of the sash, lugs on opposite 95 sides of the frame and slidably engaged in said second mentioned grooves for cooperation with said first mentioned grooves and lugs to guide the sash for movement vertically in its plane, grooved clutch members pivotally mounted on opposite sides of said frame at the lower portions of said first mentioned grooves and forming a part thereof for engagement with said clutch lugs for angular facewise movement of the sash on a horizontal axis, said second mentioned grooves being provided with lateral openings through which said second mentioned lugs pass in the angular movement of the sash, spring means operative upon said grooved clutch members 100 to yieldably urge the sash into its vertical position, window weight cords extending in said first mentioned grooves and pivotally connected with the sash approximately at the axis of angular movement thereof, and notched members releasably engageable with said second mentioned lugs to position the sash in its 105 said angular movement.
- In witness whereof I hereunto affix my signature this tenth day of October, 1927.
- THEODORE R. TREIBER.
